UNITED STATES PATENT OFFICE.

CHARLES C. SEABORN, OF PORTLAND, OREGON.

DENTAL HANDPIECE.

1,379,880.

Specification of Letters Patent. Patented May 31, 1921.

Application filed July 15, 1920. Serial No. 396,386.

To all whom it may concern:

Be it known that I, CHARLES C. SEABORN, a citizen of the United States, residing at Portland, in the county of Multnomah and 5 State of Oregon, have invented certain new and useful Improvements in Dental Handpieces, of which the following is a specification.

This invention relates to hand pieces for 10 dental engines, and the primary object of this invention is to provide an improved hand piece which can be turned at any angle and automatically locked in adjusted position against accidental displacement.

15 Another object of the invention is to provide an improved dental handpiece embodying a pair of sections, the parts of the sections being so connected that the same can be turned at any angle so that the drill, bur 20 or the like can be positioned in various relations to the handle section of the hand piece, means being provided for permitting the drill bit, bur or the like, to be driven in all of its various positions.

25 A further prime object of the invention is to provide an improved spring means for automatically locking the section of the hand piece carrying the bit in any of its adjusted positions, so that accidental swinging movement thereof will be eliminated, the spring 30 means being so arranged that the locking of the bit carrying section is automatic.

A further object of the invention is the 35 provision of an improved dental hand piece including a novel means for holding the drill bit, burs and the like in correct position on the hand piece so as to permit the convenient and easy removal thereof and to prevent the seeping of saliva or the like 40 into the hand piece.

A still further object of the invention is to provide an improved hand piece including a novel means for disconnecting and connecting of the driven shaft for the drill 45 bit, bur and the like, from the drive shaft, when desired, thereby stopping the rotation of the tool without necessitating the turning off of the power.

A still further object of the invention is 50 to provide an improved hand piece for dental engines of the above character, which is of exceptionally simple and durable construction, one that can be placed upon the market at a reasonable cost.

55 With these and other objects in view, the

invention consists in the novel construction, arrangement and formation of parts, as will be hereinafter more specifically described, claimed and illustrated in the accompanying drawings, forming a part of this specification, in which drawings:

Figure 1 is a longitudinal sectional view through the improved hand piece, showing the bit carrying section thereof in parallel relation to the handle portion thereof and 65 also showing one adjusted position of the bit carrying section in dotted lines.

Fig. 2 is a similar view showing the bit carrying section in another of its adjusted positions and showing it in its fourth and 70 final adjusted position in dotted lines.

Fig. 3 is an enlarged fragmentary sectional view through the hand piece showing the novel type of spring employed for automatically locking the drill bit carrying section of the hand piece in adjusted position. 75

Fig. 4 is a similar view showing the position of the drill bit carrying section when the same is in one of its adjusted positions. 80

Fig. 5 is a similar view showing the same in another adjusted position.

Fig. 6 is a similar view showing the same in its fourth and final position, and.

Fig. 7 is an enlarged fragmentary section 85 taken at right angles to Fig. 5.

Referring to the drawings in detail, wherein similar reference characters designate corresponding parts throughout the several views, the letter A generally indicates the improved dental hand piece, which 90 as shown includes the sections 10 and 11. The section 10 constitutes the part for carrying the drill bit or bur while the section 11 forms the handle or operating part. The section 10 is provided with a bearing 95

12 for rotatably supporting the driven shaft 13 and the inner end of this bearing is enlarged as at 14 for the reception of the collar 15 which is keyed or otherwise secured to the driven shaft. The collar 15 engages 100 the inner surface of the bearing 12 and eliminates sliding movement of the driven shaft in relation thereto. The outer end of the driven shaft 13 carries the cone shaped sleeve 16 and this sleeve is connected to the 105 shaft in such a manner that the same will freely rotate therewith. The opposite faces of the sleeve are provided with longitudinal ways 17 for the reception of the spring arms 18 and the inner ends of the spring 110

arms 18 are secured to the cone in any preferred manner against accidental displacement. The forward or outer end of the spring arms 18 are provided with right angular extensions 19 and these extensions 19 are adapted to fit in an annular groove 20 formed in the shank 21 of the bur or drill bit. This provision of the spring arms permits the easy insertion or withdrawal of a bur or drill bit into or out of the hand piece. The meeting terminals of the drill bit or bur and the driven shaft 13 are provided with interfitting shoulders, so that the movement of the driven shaft will be transmitted to the drill bit or bur. The handle section 11 of the dental hand piece A is provided with a longitudinally extending bore 22 and this bore rotatably receives the drive shaft 23. The forward end of the bore 22 is enlarged as at 24 and rotatably receives the collar 25, which is keyed or otherwise secured to the drive shaft 23. Thus it limits the movement of the drive shaft in the bore. The outer end of the bore 25 is also enlarged as at 26 and in this enlarged end is fitted the bearing 27 which rotatably carries the shaft section 28. This shaft section may be provided with the ordinary or any preferred type of coupling 30 for connection with the usual flexible shaft of the dental engine (not shown). The meeting terminals of the drive shaft 23 and the shaft section 28 are provided with squared terminals 29 and 30 respectively 35 and the squared section 30 carries a rigid clutch section 31 which is adapted to be engaged by a sliding clutch section 32 mounted on the squared end 29 of the drive shaft 23. This section is adapted to be moved by 40 an operating rod 33, the inner end of which is provided with a yoke 34 which fits in an annular groove formed in the sliding clutch section. The outer end of the operating rod 33 is secured in any preferred manner 45 as at 35 to an annular ring 36 slidably mounted on the section 11. The section 11 has its outer surface reduced to provide an abrupt shoulder 37 which limits the sliding movement of the annular ring 36 thereof. 50 If so desired, the friction stop may be provided for locking the annular ring 36 in adjusted position. It can be seen that by sliding the annular ring, the sliding clutch section 32 may be brought into or 55 out of engagement with the shaft section 38 thereby cutting off the operation of the drill bit or bur 31 when so desired without necessitating the cutting off of the power of the dental engine. An expansion 60 spring 38 is coiled around the squared portion 29 of the drive shaft 23 and the terminals of this coil spring engage respectively with the inner wall of the enlarged portion 26 of the bore 22 and against the inner face of 65 the sliding clutch section 32 and normally

tends to hold the sliding clutch section 32 in engagement with the rigid clutch section.

The meeting terminals of the sections 10 and 11 are provided respectively with substantially semi-cylindrical casings 39 and 40. The semi-cylindrical casing 39 has a relatively smaller diameter than the semi-cylindrical casing 40 and is adapted to be arranged within the same as will be herein-after more specifically described. These sections 39 and 40 are further united by annular sections 41 and 42. These annular sections 41 and 42 are curved transversely to conform to the curvature of the semi-spherical housings 39 and 40 and are arranged between and intermediate the same. These semi-spherical housings 39 and 40 and the annular rings 41 and 42 are connected together at their opposite sides by means of pivot pins 43. These sections or casings are adapted to snugly fit within one another so as to prevent the leakage of oil or lubricant from within the same and to exclude all moisture such as saliva and the like from the interior thereof. By the provision of the sections or casings 39 and 40 and the rings 41 and 42 the sections 10 and 11 may be swung at any angle in relation to each other and still present a closed casing intermediate the same. The inner ends of the drive shaft 23 and the driven shaft 13 projects into the spherical housing formed by the casing or sections 39 and 40 and the rings 41 and 42 and these portions of the shaft are formed polygonal shaped in cross section and have slidably mounted thereon the gear wheels 44 and 45. The meeting faces of these gear wheels 44 and 45 are formed convex and toothed so that the same will be connected together for movement in all of their various positions. The gears 44 and 45 are always held in intermeshing engagement by means of expansion springs 46 and 48 which are coiled around the portions of the shafts which are formed polygonal shaped in cross section and these springs bear against the outer faces of the gear wheels 44 and 45 and against the inner faces of the collars 15 and 25.

It can be seen that when the section 10 is moved at an angle in relation to the section 11 that the gears 44 and 45 will slide on their respective shafts, thus conforming to the shortening of the angle.

To hold the sections 10 and 11 in their various adjusted positions substantially semi-circular springs 49, 50 and 51 are provided. As stated, these springs are semi-circular shaped and are of the leaf spring type and their central portions are provided with lugs 52 which are riveted or otherwise secured to various parts of the spherical housing. As shown the spring 49 is secured to the ring 41, the spring 50 to the ring 42, 125 and the spring 51 to the ring 11. 130

and the spring 51 to a semi-spherical casing or section 40. When the section 10 is in alinement with the section 11, all of the springs tend to hold the sections in correct position against accidental displacement. Owing to the formation of the springs it can be seen that the opposite ends thereof will engage the inner faces of the sections 42, 41 and 39. The section or ring 42 is provided at the central portions thereof with inwardly extending triangular shaped lugs 53 and the free terminals of the spring 51 is provided with outwardly extending lugs 54 which is adapted to engage at different times the opposite faces of the triangularly extending lugs. When the section 10 is in its alined position with the section 11, the lugs 54 will engage the upper faces of the lugs 53 but when the hand piece 11 is turned at a slight angle the lugs 53 will force the terminals of the spring outwardly, and the terminals will then engage the lower faces of the lugs. This position is clearly shown in Fig. 5 of the drawings, and the movement of the section 42 is further limited by a stop lug 55, which is carried by the inner surface of the semi-cylindrical casing or section 40. The ring 41 has its inner face inclined toward the central portion thereof so as to provide inclined faces 56 and 57 and these faces are adapted to be engaged at different times by the leaf spring 50 and it can be seen that when it is desired to further increase the angle of the section 10 in relation to the section 11 the spring 50 will be raised and the same will engage the inclined faces 57 of the section and thus tend to hold the same in this position. The movement of the section or ring 41 is further limited by means of a lug 58 which is carried by the inner face of the ring or section 42. When it is desired to swing the section 10 at right angles to the section 11 the same is swung still farther down which will move the semi-spherical casing or section 39 on its pivot and the same is held in its adjusted position, as clearly shown in Fig. 6 of the drawings, by means of the spring 49. This spring 49 has its terminals provided with a pair of angularly related bight portions 59 and 60 and these portions are adapted to engage respectively the angular related edges formed by the inclined faces 61 of the casing or section 39. The movement of this section or casing 39 is in turn limited by means of a lug 62 carried by the inner face of the ring or section 41.

It can thus be seen from the foregoing description that the section 10 can be turned at various angles in relation to the section 11 and held in any one of its adjusted positions and still permit of the driving of the drill bit or bearing.

65 As clearly shown in the drawings, the

outer surface of the section 10 is provided with a hard rubber or suitable sleeve 63 and the inner end of the sleeve is provided with an annular flange 64 which is adapted to engage the drill bit or bur and act to wholly prevent the entrance of saliva into the housing. 70

While as shown a novel means for connecting the drive and driven shaft together is provided, it is to be, of course, understood that various means may be employed, such as the usual type of universal joint or a spring coupling. 75

Changes in details may be made without departing from the spirit or scope of this invention; but,

I claim:

1. A dental hand piece comprising a pair of sections, means hingedly connecting the sections together including a plurality of collapsible leaves, a drive shaft carried by one section, a driven shaft carried by the other section, and means operatively connecting the shafts together. 85

3. A hand piece for dental engines comprising a handle section and a tool section, means hingedly connecting the sections together so as to permit the same to swing in various angles in relation to each other including a plurality of leaves, means automatically locking the leaves to hold the sections in their various adjusted positions, rigid stop members arranged to limit the movement of the leaves in relation to each other, a drive shaft carried by the handle section, a driven shaft carried by the tool section, and means operatively connecting these sections together. 100 105 110

4. A hand piece for dental engines comprising a handle section and a tool receiving section, a knuckle joint connecting the sections together, said knuckle joint including a plurality of arcuate hingedly connected members, and locking springs arranged to engage the sections for holding the handle section and the tool section in adjusted positions in relation to each other. 115 120

5. A dental hand piece comprising a handle section and a tool receiving section, a spherical knuckle joint connecting the two sections together, said joint including a plurality of hingedly connected arcuate leaves forming a complete casing, automatic locking springs carried by certain of the leaves arranged to engage adjacent leaves for hold- 130

ing the handle section and the tool receiving section in various adjusted positions in relation to each other, and a drive and a driven shaft carried by the sections connected together for synchronous movement.

6. A dental hand piece comprising a handle section and a tool receiving section, a knuckle joint connecting the two sections together, said joint including a plurality of 10 hingedly connected leaves, the leaves forming an inclosed spherical casing, spring means for automatically holding the sections in adjusted positions in relation to each other, a drive shaft carried by the 15 handle section, a driven shaft carried by the tool receiving section, the inner portions of said shafts extending into the spherical casing formed by the hingedly connected leaves, said portions of the shafts being 20 formed polygonal shaped in cross section, a pair of gear wheels slidably mounted on the polygonal section of the shafts, the inner meeting faces of the gear wheels being convexed, and spring means normally holding 25 the gear wheels into intermeshing engagement.

7. A dental hand piece comprising a handle section and a tool receiving section, the inner ends of the sections having substantially 30 semi-spherical casings formed therein, a plurality of annular arcuate sections disposed intermediate the semi-spherical casing, means hingedly connecting the semi-spherical casing and the annular arcuately 35 curved sections together, a stop lug carried by the semi-spherical casing formed on the handle section arranged to limit the swinging movement of one of the annular sections, stop lugs carried by the annular sections 40 arranged to limit the swinging movement of one of the annular sections, and the semi-spherical casing carried by the tool receiving section, arcuately curved leaf springs carried by one of the semi-spherical 45 casings and the annular sections arranged to engage the adjacent annular sections and one semi-spherical casing for normally holding the handle and the tool receiving

sections against movement in all of their various adjusted positions, and a drive and 50 driven shaft carried by the handle and tool receiving sections operatively connected together.

8. A casing for dental hand pieces comprising a handle section and a tool receiving section, the inner ends of the sections having substantially semi-spherical casings formed thereon, a plurality of annular transversely arcuately curved sections disposed intermediate the casings, means 60 hingedly connecting the casings and the annular sections together, the inner faces of the sections and one of the semi-spherical casings having the opposite sides thereof inclined, arcuate leaf springs secured to one 65 of the semi-spherical casings and the annular section, the springs being adapted to engage the opposite inclined faces of the sections and the semi-spherical casing to hold the handle section and the tool receiving 70 section in various adjusted position adjacent to each other and limiting stop members carried by one of the semi-spherical casings and the annular sections.

9. A dental hand piece comprising a handle section and a tool receiving section, a knuckle joint connecting the sections together, a drive shaft, a driven shaft, means 75 operatively connecting the shafts together, the drive shaft being formed into two sections, and a sliding clutch member arranged to connect and disconnect the sections of the drive shaft when so desired.

10. A dental hand piece comprising a handle section and a tool receiving section, 85 a knuckle joint hingedly connecting the sections together, a drive shaft, and a driven shaft, means operatively connecting the shafts together, a cone member carried by the driven shaft, a pair of spring arms carried by the cone member, the spring arms having inwardly extending feet arranged 90 to engage a drill bit to hold the same against displacement.

CHARLES C. SEABORN.
